SWEATER DRIER AND STRETCHER

Isidore Schwartz, New York, N. Y.

Application July 22, 1938, Serial No. 220,642

2 Claims. (Cl. 223—69)

This invention relates to improvements in sweater driers and stretchers, and it is the particular object of the invention to provide an improved relatively inexpensive article of the above character which may be used in drying sweaters and which will serve to prevent the sweater from shrinking or becoming distorted while drying.

Another object is the provision of an improved sweater drier which, while providing the desired support for the sweater while it is drying, will not unduly retard the drying process.

It is a further object of the invention to provide an improved sweater drier having removable sleeve supports so that the drier may be used with sleeveless sweaters or with sweaters provided with sleeves.

Among other objects is the provision of an improved sweater drier which will not be injured by moisture and which is nevertheless of relatively light, compact construction, so that it may be folded into a relatively flat, small parcel when not in use.

In the accompanying drawing—

Fig. 1 is a front elevation of a sweater drier embodying my invention, showing the removable sleeve supports attached thereto;

Fig. 2 is a longitudinal sectional view in the direction of the arrows on the line 2—2 of Fig. 1;

Fig. 3 is a side view of the drier in collapsed position;

Fig. 4 is a front view of the drier in collapsed position;

Fig. 5 is a detail view of one of the sleeve supports in extended position;

Fig. 6 is a side view of the sleeve support in collapsed position;

Fig. 7 is a view of the upper portion of the body member of the drier showing a modified type of hook applied thereto; and

Fig. 8 is a side view of the modified structure shown in Fig. 7.

My improved drier preferably embodies a body portion 10 and sleeve supports 11 and 12 removably attached to the body portion. The body and sleeve supports are formed to the desired shape and size of the sweater to be dried thereon and are made of flat sheets of light but strong material, such as cardboard, fiber board, pressed paper or the like, which is treated with paraffin or some similar substance so as to make the material water-repellent.

The body portion may be shaped as shown with rounded shoulders 14 and with a tapered relatively narrow waist 15. The sleeve supports are preferably of generally tapered construction

as shown, and any desired type of releasable fastening means may be employed for attaching the sleeve supports to the body portion. However, for this purpose I prefer to employ snap fasteners as shown at 16. So as to provide circulation of air and in that way facilitate rapid drying of the sweater supported on the drier, I provide both the sleeve supports and the body portion with perforations as shown at 18.

As previously stated, my drier is preferably collapsible and can be folded into a relatively compact parcel when not in use. To accomplish this result I provide the center of the body portion with a transverse fold line 19, and I provide the sleeve supports with similar transverse fold lines 20. In this way, when the device is not in use the sleeve supports may be removed from the body portion and the respective parts can then be folded on the fold lines 19 and 20 so as to form a relatively small parcel, as shown in Figs. 3, 4, and 6.

I have found that it is desirable to provide my drier with a hanger on which it may be supported when in use, and the hanger may take the form of a hooked projection 21 formed integral with the body portion 10 and extending upwardly therefrom at the center thereof. When the hanger is thus formed I preferably form a fold line 22 at the lower portion of the hanger so that the hanger may be folded inwardly, as shown in Figs. 3 and 4, when the device is not in use. Instead of forming the hanger integral with the body portion, I may form it out of a strip of metal wire provided with a rounded hook at the top thereof, as shown at 23 in Figs. 7 and 8. When the hanger is thus formed it is preferably secured to the center of the body portion by a pin, rivet or the like, as shown at 24, so that it may pivot downwardly, as shown most clearly in Fig. 7.

It will be appreciated that my improved sweater drier and stretcher should be made in various sizes and that in drying a sweater a drier of the proper size should be selected.

The use of my drier will be readily understood. Where a sleeveless sweater is to be dried, the sleeve supports should be removed from the drier and the drier should be inserted in the washed sweater so that the hanger 21 or 23 projects through the neck opening of the sweater. Where a sweater having sleeves is to be dried, the body portion is first inserted in the sweater in the manner described above, and the sleeve supports are then inserted through the sleeves of the sweater and attached to the body portion.

It will be appreciated that the drier can be supported in a convenient manner by means of the hanger.

5 Due to the provision of the perforations 18, there will be sufficient air circulated to provide for relatively rapid drying of the sweater. It will thus be seen that by means of my improved sweater drier a sweater can be dried in a relatively simple and convenient manner without 10 shrinking and without being stretched or distorted. If desired, advertising matter or instructions for washing sweaters, or for using the drier, may be printed on the surface of the drier.

15 It should be understood that modifications may be made in the illustrated and described embodiment of my invention without departing from the invention set forth in the accompanying claims.

20 I claim:

1. A sweater drier, comprising a body portion having a hook-shaped hanger projecting from the top thereof and sleeve supports detachably secured to the body portion by means of snap fasteners, said body portion and sleeve supports

each being formed of a relatively flat sheet of light, strong, water-repellent material and having perforations formed therein so as to provide for air circulation, and the body portion and sleeve supports being provided with transverse fold lines, and the hanger being foldable against the body portion whereby the drier may be collapsed into a relatively small parcel.

2. A sweater drier comprising a body portion and sleeve supports detachably secured to the body portion by means of snap fasteners, said drier being made of a relatively flat sheet of light, strong, water-repellent material having perforations formed therein so as to provide for air circulation, the body portion being of the same size and contour as the body portion of the sweater to be dried, and said sleeve portions being of the same size and contour as the sleeve of the sweater to be dried, and both the body portion and sleeve supports being provided with transverse fold lines whereby the drier may be collapsed into a relatively small parcel.
